US00D892913S

(12) **United States Design Patent** (10) **Patent No.:** **US D892,913 S**
(45) **Date of Patent:** **** Aug. 11, 2020**

(54) **GOGGLE**

(71) Applicant: **Smith Sport Optics, Inc.**, Portland, OR (US)

(72) Inventors: **Hans Lindauer**, Brooklyn, NY (US); **Alberto Ventura**, Portland, OR (US); **Mike Aaskov**, Kennebunkport, ME (US); **Will McNeal**, Portland, OR (US); **John Ohran**, West Linn, OR (US); **Eric Thorsell**, Portland, OR (US); **Matt Capozzi**, Bend, OR (US); **Nicolas Ramirez**, Portland, OR (US); **Scott Layton**, Portland, OR (US)

(73) Assignee: **Smith Sport Optics, Inc.**, Portland, OR (US)

(**) Term: **15 Years**

(21) Appl. No.: **29/669,091**

(22) Filed: **Nov. 5, 2018**

(51) LOC (12) Cl. **16-06**

(52) U.S. Cl.

USPC **D16/313**

(58) **Field of Classification Search**

USPC D16/300, 313, 325, 326, 328

CPC G02C 5/008; G02C 5/146

See application file for complete search history.

CLAIM

We claim the ornamental design for a goggle, as shown and described.

DESCRIPTION

FIG. 1 shows a top isometric view of a goggle in accordance with the present design.

FIG. 2 shows a bottom isometric view of the goggle in FIG. 1.

FIG. 3 shows a rear isometric view of the goggle in FIG. 1.

FIG. 4 shows a front view of the goggle in FIG. 1.

FIG. 5 shows a rear view of the goggle in FIG. 1.

FIG. 6 shows a top view of the goggle in FIG. 1.

FIG. 7 shows a bottom view of the goggle in FIG. 1.

FIG. 8 shows a right side view of the goggle in FIG. 1; and, FIG. 9 shows a left side view of the goggle in FIG. 1.

The broken lines illustrate portions of the goggle that form no part of the claimed design.

1 Claim, 8 Drawing Sheets
